UNITED STATES PATENT OFFICE.

LEON THIRY, OF HUY, BELGIUM.

BEATING-ENGINE TO REFINE PAPER-STOCK.

1,200,778.

Specification of Letters Patent.

Patented Oct. 10, 1916.

Application filed October 21, 1912. Serial No. 727,046.

To all whom it may concern:

Be it known that I, LEON THIRY, engineer, a subject of the King of Belgium, and resident of Huy, in the Kingdom of Belgium, 5 have invented certain new and useful Improvements in Beating-Engines to Refine Paper-Stock; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

This invention relates to beating engines for refining paper stock.

One object of the invention is to provide simple and efficient means for felting the 20 fibers.

Another object of the invention is to provide rollers for felting the fibers which are adjustable independently and having means for obtaining the pressure which is most 25 convenient to the various fibers.

The principal qualities of a good paper are transparency and solidity which qualities are obtained by perfect felting of the fibers and said felting depends upon the refinement of the stock. To accomplish this result, the fibers must be cut to obtain a perfect transparency and they must be divided in convenient lengths to provide for as close a felting as possible.

35 With these and other objects in view, the invention consists of certain novel features of construction, and the combination and arrangement of parts as will be more fully described and claimed.

40 In the accompanying drawings: Figure 1 is a top plan view of a beating engine constructed in accordance with this invention; Fig. 2 is a section on an enlarged scale taken on the line *c-d* of Fig. 1, the trough being 45 also partially represented in section.

In the embodiment illustrated, a beating engine is shown having two rollers A and B one of which is provided with metallic knives and the other is constructed of basalt lava stone. The steel barred roller usually employed operates upon a bed plate of the same material and serves as a fiber cutter and prevents the greasy refining of the stock unless the stock is refined too short. The basalt lava roller operates upon a bed plate of the same material and crushes the fibers without

cutting them. These facts which were experienced by me, led to the designing of a beating engine with two rollers one of which I provide with steel knives and the other of which is made of basalt lava stone. The successful result of the combination of said rollers depends mostly upon the accuracy with which the action of each element or roller is regulated or in other words, upon the specific pressure worked out by each roller. To accomplish this, a special device for equilibrating the rolls by means of rolling counterweights was used which renders it very easy to produce by each roller the pressure which has been found to be the best for each kind of stock or paper said pressure itself being easily controlled. Even after a long time, it is possible to produce periodical qualities under the same condition of work.

In the accompanying drawings each journal of the two rollers A and B is supported upon a lever 1 which is fulcrumed or articulated at 2 and its free end rests at 3 upon a small supporter 4 which is itself fulcrumed at 5 upon a crank 6. The cranks 6 are keyed on each end of a shaft 7 which passes through the entire trough of the beater through a special housing prepared for this purpose. To one of the cranks 6 is connected a rod 8 in order to control the distance between the roller and the bed plate. The lower end of the rod 8 slides freely in an aperture in a small console 19 of the supporter so that the cranks can pivot around the point 7 until their movement downward is limited by a portion 18 of large radius created at the bottom of the rod. The other end of this rod is threaded and is supported by a wheel 9 which is provided with a threaded hole and is itself supported by the frame 17. The wheel 9 is operated by a snake or endless screw 10 to which a hand wheel 11 imparts movement.

To balance the roll, a counterweight 12 is employed which is fitted with roller bearings 20 and rolls upon a graduated lever 13. This lever 13 rests upon a knife edge 14 such as is commonly used in weighing machines and a rod 15 connects said lever adjacent said point 14 with the crank shaft 6. The length of this rod may be regulated according to the will of the operator being provided with a turn buckle or adjusting device 16 for this purpose. The longer end of the lever 13 which extends beyond its ful-

erum and on which the counterweight 12 is mounted, permits the use of a counterweight of small size which is especially useful in that it permits the operation thereof 5 with little effort and the lever 13 being graduated with great precision renders it possible to regulate the pressure at the will of the operator very accurately.

To reduce the cost of the shafts of the 10 rolls as much as possible, the length of said shafts has been reduced by preparing bearings at the interior portion of the beater trough where they are driven by pulleys or belts.

15 A special study of the beater trough was made in order to facilitate the run of the stock to increase the circulation and to render shoveling unnecessary although stock deposit is avoided. To accomplish this result, I have made the saddle much higher than usual and a channel which follows the saddle much narrower.

From the above it will be obvious that in the top beating engines described it is very 25 important to provide means for regulating independently the pressure under which each of the rollers is working and each of the rollers must be more or less equilibrated so that the weight 12 counter-balances to a 30 greater or less extent, the weight of the roller, according to the kind of paper which is to be obtained. When a paper requiring a very greasy paste or pulp is desired, the lava stone roller must press with its entire 35 weight in order to refine the fibers greasy and the roller provided with metal knives must be almost completely equilibrated in

order to cut the fibers very little and to permit them to remain of considerable length. On the other hand should a paper requiring a short and medium paste be desired, the lava stone roller must be almost completely equilibrated in order that the paste be slightly greasy and the roller provided with the metal knives must be considerably weighted 40 in order to cut and shorten the fibers. The pressure of both rollers must be properly adjusted or regulated for all kinds of intermediary stocks of paper and the gist of this invention resides in providing a beating engine with two rollers each of which may be independently adjusted.

I claim as my invention:

In a beating engine the combination of a supporting structure, a plurality of rollers mounted in said structure, levers fulcrumed at one end to support the journals of the rollers, fulcrumed members supporting the free ends of said levers, cranks carrying said fulcrumed members, and counterbalancing means connected with said fulcrumed members for varying the position of the suspending means of said rollers, whereby the pressure of the rollers on the paste is controlled, the counterbalancing means of one roller being entirely independent of that of the other roller.

In testimony whereof I affix my signature in presence of two witnesses.

LEON THIRY.
